SELF-PROPELLED VIBRATORY COMPACTOR

George D. Herbst, Milwaukie, Oreg., assignor to Hyster
Company, Portland, Oreg.

Filed Nov. 19, 1971, Ser. No. 200,666

Term of patent 14 years

Int. Cl. D12—09

U.S. Cl. D14—3

Fig. 1

Fig. 2

FIG. 1 is a plan view of a self-propelled vibratory compactor in accordance with my new design;

FIG. 2 is a right side elevation of the compactor of FIG. 1;

FIG. 3 is a left side elevation of the compactor;

FIG. 4 is a front end view; and

FIG. 5 is a rear end view of a compactor in accordance with my new design.

I claim:

The ornamental design for a self-propelled vibratory compactor, as shown and described.
